WASTE BASKET

John W. Ebstein, Roslyn Heights, N.Y., assignor, by mesne assignments, to Federal Enameling & Stamping Co., Pittsburgh, Pa., a corporation of Michigan

Filed Feb. 10, 1960, Ser. No. 59,340

Term of patent 14 years

(Cl. D58—17)

FIG. 1.

FIG. 2.

FIG. 3.

FIG. 4.

The side and end not shown are the same as the side and end shown.

I claim:

The ornamental design for a waste basket, as shown and described.
